UNITED STATES PATENT OFFICE.

ADELE TERESA STROUT, OF LITTLETON, MASSACHUSETTS.

REFRIGERATOR.

1,235,736.

Specification of Letters Patent.

Patented Aug. 7, 1917.

Application filed March 27, 1915. Serial No. 17,525.

To all whom it may concern:

Be it known that I, ADELE T. STROUT, a citizen of the United States, residing at Littleton, in the county of Middlesex and State 5 of Massachusetts, have invented certain new and useful Improvements in Refrigerators, of which the following is a specification, reference being had therein to the accompanying drawing.

10 This invention relates to improvements in refrigerators, and has for its object the provision, in combination with suitable supporting means within the refrigerator, of a tray provided with removable dishes adapted to receive the different materials desired to be 15 preserved; and said tray, in the portions thereof surrounding and underlying the dishes, being preferably of open-work,—conveniently wire mesh,—enabling free passage of the cold air through the refrigerator and directly around the dishes referred to.

It is quite a universal practice in preserving what might be termed "left overs" to either insert the relatively large dishes originally containing the food in the refrigerator with the smaller particles to be saved; or to place said particles in other dishes laid indiscriminately upon the shelves of a refrigerator, rendering any particular dish at 20 30 times relatively inaccessible without disturbing things in front of the same and constantly presenting the liability of tipping or upsetting and breakage. Thus my idea may be said to overcome the necessity for using 35 the variety of differently shaped and sized dishes, so often found in refrigerators,—frequently expensive china,—and many times large dishes containing but little food and taking up useful space.

40 The dishes which I contemplate using in my device, will, in coöperation with the tray in which they are removably seated, always occupy an expected place in the refrigerator, so that food may be scraped into them instead of placing the china or other table 45 dishes themselves into the refrigerator. The interfitting of the removable dishes with the trays will enable all of the dishes to be maintained in their appropriate place, and prevent any of the dishes slipping around, thus tending to the spilling of more or less food, when a dish is being removed, and preventing chipping of the edges of dishes so often encountered in usual practice.

55 The details in the construction and ar-

rangement of the preferred embodiment of the invention will be apparent from the specific description hereinafter contained, when read in connection with the accompanying drawings forming part hereof and wherein 60 the preferred embodiment of the invention is illustrated.

In the drawings:

Figure is an elevation of my improved device in place in a refrigerator, the latter 65 being shown in a fragmentary manner, three of the dishes being shown in place, and three removed;

Fig. 2 is a plan view of the device shown removed from the refrigerator, and, 70

Figs. 3 and 4 are respectively transverse and longitudinal sectional views.

Referring more specifically to the drawings wherein like reference letters designate corresponding parts in the several views, A 75 represents the body portion of a refrigerator, having therein supporting ledges or their equivalents B, conveniently on the opposite side walls,—and C represents my improved tray, adapted to be slidably inserted into and 80 removed from the refrigerator, over said ledges or other supports B. This tray is composed of open wire mesh, of a size to furnish the requisite supporting strength, being reinforced around its margin by a 85 heavy wire D, and transversely and longitudinally, by similar wires E and F, respectively, subdividing the tray into any number of dish-supporting sections desired,—six being shown in this case merely for the purpose 90 of illustration. Obviously any other number may be utilized to accord with the particular service condition desired.

The center portion of the wire mesh in each section corresponds in contour to the 95 bowl portion of the dishes to be used, and is depressed, as at G, to constitute seats, the bordering portions of the wire mesh adjoining the edges of the seats sloping upwardly, as at g. H represents the dishes, which are 100 preferably in the nature of flat plates, in number corresponding to the sections of the openwork tray, the central portions of the plates carrying bowls or containers h conveniently formed with and suspended from 105 the plates, the bowls being adapted to enter the seats G, and the plate surrounding, or flange portions H, being adapted to overlie the sloping upper surface g, bordering the seats G, these sloping portions facilitat- 110

ing the introduction of the fingers between the plates H and the wire tray in removing any given dish from the tray.

The dishes are preferably formed of white 5 enamel intended as permanent parts of the refrigerator, and the plates or flange portions H thereof are of a width and length so that when assembled, the spaces J will be left therebetween for engagement of the 10 plates by the fingers of the user, as previously observed, also for the free circulation of air past the dishes.

By the construction just defined, it will be 15 readily understood that I have provided a refrigerator attachment presenting advantages over the old method of storing small quantities of food. However, the underlying idea of the dish receiving tray may be carried forward to embrace much larger 20 containers than those illustrated by way of example herein. It will also be clearly appreciated that while providing the tray and container carried thereby, I am enabled by reason of the openwork character of the tray 25 to hold the dishes practically in an entirely open space, suspended for the passage of the cold air entirely around and over all portions of the dishes or containers.

While I have herein disclosed a special 30 embodiment of the invention, it will be clear to persons skilled in the art that the same is capable of embodiment in other forms and devices, as may be in keeping with the scope of the hereto appended claims.

Having thus described the invention, what 35 is claimed is:

1. The combination with a refrigerator, of a supporting tray mounted therein of openwork material having depressions there-

in to constitute seats, and dishes adapted 40 to fit said seats, the dishes having top flanges, and the tray having sloping top portions adapted to underlie said flanges to leave spaces for the introduction of the finger in removing the dishes. 45

2. In a device of the character described, an openwork tray having a depressed portion, in combination with a dish having a bowl portion adapted to fit said depressed portion of the tray, the tray having sloping upper marginal portions and the dish having a marginal flange portion adapted to overlie the same to leave spaces for the introduction of the fingers in removing the dishes, other depressed portions also 50 formed in the tray, and other dishes adapted to fit the same and provided with top flanges of a size, when assembled, to leave spaces between the flanges of the adjacent dishes. 55

3. In a device of the character described, a tray formed of open wire mesh material having relatively deep depressed portions to constitute dish seats, and intermediate or marginal relatively shallow depressed portions to constitute finger spaces, in combination with a series of dishes formed complementary to said seats and adapted to be supported therein with their edges above said relatively shallow recesses, substantially as and for the purpose described. 60

In testimony whereof I hereunto affix my signature in the presence of two witnesses.

ADELE TERESA STROUT.
